JOHN E. CRYER, OF GREEN POINT, NEW YORK.

Letters Patent No. 67,105 dated July 23, 1867.

IMPROVEMENT IN CHURNS.

The Schedule referred to in these Letters Patent and making part of the same.

TO ALL WHOM IT MAY CONCERN:

Be it known that I, JOHN E. CRYER, of Green Point, Brooklyn, E. D., in the county of Kings, and State of New York, have invented certain new and useful Improvements in Churns; and I do hereby declare that the following is a full and exact description thereof.

My churn works by partially oscillating a shaft having suitable dashers. The shaft extends outside of the churn and is threaded spirally, and is adapted to be operated by causing a suitable nut to reciprocate longitudinally backwards and forwards on the threaded portion. I have also devised a very effective and convenient means of applying the several parts together and of operating the nut. I will first proceed to describe what I consider the best means of carrying out my invention, and will afterwards designate the points which I believe to be new. The accompanying drawings form a part of this specification.

Figure 1 is a side elevation, and

Figure 2 is a vertical section at right angles thereto.

Similar letters of reference indicate like parts in both the figures. Tints are employed merely to aid in distinguishing parts, and do not indicate material. The material of most of the mechanism may be wood.

A is the body of the churn. A¹ and A² are uprights firmly fixed thereto. B is a vertical shaft, carrying arms B¹ and dash-boards B², the latter being perforated as represented, and adapted to operate sufficiently on the cream to break the globules and produce butter in the shortest and most efficient manner. C is a cross-bar, supported in slots in the uprights A¹ A², and held in position by means of notches C¹ C², which fit the lower ends of the slots in the uprights, a bar being held firmly down by means of the wedged piece D. There is a conical pivot, a, in the centre of the base of the body A, and a corresponding pivot, c, in the centre of the base of the cross-bar C. These pivots fit in corresponding holes in the ends of the shaft B. A deep and smooth spiral groove is formed in the shaft B, above the cover of the churn, as indicated by b. A nut, E, loosely surrounds the shaft B at this portion, and is provided with the feather e, which may be made in the form of a simple pin or screw, as represented, or which may be extended a considerable distance up and down if preferred, so as to give a wider bearing in the spiral groove b. It will be understood that the feather e stands in the groove b, and compels the shaft B and its connections to partially rotate in opposite directions as the nut E is moved up and down on the shaft. G is a hand-lever, mounted on the upper end of the upright A². H is a fork, strongly fixed on G at the point h, and so that it allows for the vibration of the lever and of the link, but forbids the turning of the link around. The arms H¹ H² of the link take hold on trunnions E¹ E², on the nut E.

The operation of my churn will now be readily understood. The cover A⁴ of the churn may be fitted in halves, or in any other approved manner, so that it may be partially or entirely removed at will, and the cream is poured into the churn at the top in the ordinary manner. After the cream is introduced and the cover is in place, the handle G is reciprocated, and the dashers B² are compelled to traverse violently through the milk, first turning in one direction and then in the other. This motion rapidly induces the desired condition in the mass, and after the butter has fully "come" the cover is removed. Either before or after the separation of other parts of the churn, the butter and buttermilk are removed, and the churn is scalded and put away. To separate the parts of the churn, I drive out the wedge D, lift and remove the bar C, and after withdrawing a pin at g can remove the shaft B, with its connection. Reversing this process replaces the parts, and puts the churn again in condition for use. I propose to employ a swell thread or bead, extending spirally around the shaft B, in lieu of the shaft b, if preferred, it being of course understood that in such case the nut E is recessed to match such raised thread. I can employ two or more spiral threads b in lieu of one, with corresponding increase in the number of feathers e, or their equivalent, if preferred. My fork link H¹ H² forms a very ready and simple means of communicating motion from the hand-lever G to the traversing-nut E e, and at the same time efficiently preventing the nut from turning around under the force to which it is subjected. I have tested my improved churn practically, and find its novel mechanism very efficient and free from objection.

Having now fully described my invention, what I claim as new in churning, and desire to secure by Letters Patent, is as follows:

1. I claim the spiral-threaded shaft B b, in combination with the traversing-nut E e, and with oscillating dashers, arranged to operate substantially in the manner and for the purpose herein specified.

2. I claim the fork link $H H^1 H^2$, connected to the nut $E e$, and arranged to operate relatively thereto, and to the spiral-threaded shaft $B b$, and to the hand-lever G , or its equivalent, substantially as and for the purposes herein specified.

3. I claim mounting the within-described partially-revolving shaft $B B^1$ between pivots $a e$, in the manner represented, one of the said pivots being fixed on a cross-bar, $C C^1 C^2$, secured in bearings $A^1 A^2$ by means of the removable wedge D , so as to allow the whole to be connected and disconnected, substantially in the manner and for the purposes herein set forth.

In testimony whereof I have hereunto set my hand in the presence of two subscribing witnesses.

JOHN E. CRYER.
